COIN CONTROL

Joseph W. Srodulski, Chicago, Ill.

Application November 30, 1938, Serial No. 243,236

6 Claims. (Cl. 194—97)

This invention pertains to coin control apparatus for use in vending and other coin-operated and controlled devices, and has as one of its important objects the provision of a manual control and an actuating member arranged to be coupled for operation of the latter by the former by a suitable coin.

A further important object is the provision of a reciprocable manual control and a reciprocable actuating member arranged for movement in the same direction as the manual control, and means on the manual control and actuating member engageable with a coin element to couple the control and actuating member for joint movement, together with coin testing mechanism arranged to deliver a suitable coin into operative relationship with the control and actuating member.

Another object is the provision of means cooperating with a manual control slide and an actuating slide, adapted to be coupled by a coin element, for preventing retrograde movement of either the manual control or actuating slide after the same have been moved a predetermined distance in their operative strokes.

A further object is a novel combination of cooperating operating slide members arranged to reciprocate in the same direction and arranged to be coupled together for joint movement by a coin element, coin testing means arranged to test and deliver certain coin elements into operative coupling relation with the slides, and blocking mechanism coacting with the testing means and slides for preventing delivery of an otherwise acceptable coin element from the testing device into position for coupling relation with the slide members when the latter are already coupled by a coin element.

Other novel aspects and objects of the invention reside in certain details of construction, form, location, and operation of the component parts of the illustrative embodiment hereinafter described in conjunction with the annexed drawings, in which:

Fig. 1 is a rear perspective of the entire control unit;

Fig. 2 is a vertical side section through the device of Fig. 1; while

Fig. 3 is a fragmentary rear perspective of the coin-coupled slides with portions cut away to show the full stroke means.

Referring to Fig. 2, a preferred arrangement includes a housing 10 pivotally attached as at 11 to a relatively stationary cabinet member 12 in which is situated a coin receptacle 13 having a

coin receiving opening 14 disposed below a floor member which is secured to the housing portion 10 and constitutes a floor for the latter.

Slidably mounted in the lower sleeve section 5 of a guide casting 16 (Figs. 1 and 3 also) is an actuating member or ejecting slide 17 in the form of an inverted pan provided with an elongated slot 18 extending centrally therein in the direction of reciprocable movement of the slide in 10 the sleeve portion 16. The down-turned marginal wall portions 19 of the ejecting member slide on the floor 15. Formed transversely near one end of the slot 18 in the ejecting slide or pan, is a coin slot 20.

15 The ejecting slide 17 is intended to move in and out of the sleeve casting 16 (toward the left as viewed in all figures), the ejecting slide being normally positioned as seen in Figs. 1 and 2.

Means for operating or reciprocating the actuating member or slide 17 includes the provision of a reciprocable manual operating or control slide 25 also slidably mounted as at 26 (Figs. 1 and 3) in opposite offset flanges 16' of the guide casting 16, the manual control slide being movable back and forth codirectionally with the actuating slide 17.

Depending from the under side of the rear (right-hand) end of the manual control slide is a pair of spaced pins 28 which project into the longitudinally extensive slot 18 in the cooperating ejecting slide 17, the pins 28 being spaced in the longitudinal direction of the slides. When the control slide 25 is withdrawn (toward the left), the pins 28 will be moved into register with the transverse coin slot 20 in the ejecting slide, and there is a transverse coin receiving slot 29 arranged in the operating slide above the space between the pins 28 so that should a coin be deposited in the slot 29 when the latter and the pins 28 are in alignment or register with the slot 20 in the actuating slide, the coin would gravitate into the latter slot, and should the coin be of a predetermined requisite diameter it would rest on the floor portion 15 with upper parts of the coin lying in the slot 29, as well as the slot 20 of the cooperating slide members, with the result that an inward (right-hand) movement of the control slide would also effect corresponding movement of the actuating or ejecting slide 17.

Thus, the cooperating slide members are arranged and constructed to be coupled by a suitable coin element.

When the manual control slide has reached 55 the limit of its inward (right-hand) movement,

the depending pins or fingers 28, as well as the slots 20 and 29, will be positioned above a drop-out opening 30 provided in the floor portion 15 in register with the deposit opening 14 in the coin receptacle 13 so that the coupling coin will gravitate out of the slots in the slide members theretofore coupled by the same, and into the coin box. The foregoing movement of the slides constitutes an operating stroke, and the control mechanism is intended to be associated with a coin-operated vending machine or analogous device in which the slide 17 actuates some controlled instrumentality. In the illustrative arrangement of Fig. 2, articles of merchandise M are stacked behind the control unit so that the lowermost article will be engaged by the rear vertical wall portion 19 of the slide 17 and dislodged from the bottom of the stack. Obviously, the actuating slide 17 may be arranged to operate a multitude of instrumentalities.

Means for preventing retrograde movement of either of the slides once the same have been started upon their inward operating stroke, includes the provision of depressions 31 in the floor plate 15, the depressions being arranged in serial alignment and tilting downwardly in a direction opposite to the direction of effective movement of the slide members; in other terms, the effective operating stroke of the slide members is toward the right in Fig. 2, and the serially aligned depressions 31 tilt downwardly toward the left. As a coin rides along the floor 15 under urging of the coupled slide members, the lower edge thereof will ride into and out of the formations 31 interfering with the movement of the slides toward the right; however, as soon as the slides 25 or 17 are retracted before reaching their full stroke, the coin will drop into the lower portion of one of the depressions 31 and bear against the edge portion 32 thereof and effectively lock the slides against further retractive movement. By this means it is impossible to retract the slides after the same have been started in their operative stroke until the full operating stroke is completed.

Means for testing and delivering coin elements into coupling relation with the slides includes a coin testing unit 35 mounted within the housing 10 above the slide member. This testing unit is preferably, though not necessarily, of the construction shown in U. S. Patent 2,073,392, issued to one Knee, and this type of testing device comprises a casing 35 which includes a coin chamber 36 which is disposed beneath a coin deposit opening 37 in the housing 10 when the testing unit is in assembled relation with the latter, and in which chamber coin elements are retained in testing position opposite a plurality of testing fingers 38 by legs 39K of a U-shaped member 38K projecting into the chamber and against which the edge of a coin rests when the latter is first deposited in the device.

The coin testing device of the Knee patent includes a vertically reciprocable plate 39 arranged in the casing 35 for downward movement. Depression of this plate 39 will urge a baffle 90, pivoted at 91, counter-clockwise by reason of a cam action at 90a to draw a bolt 88, seated in the free end of a lever 89 adapted to move with baffle 90, to the right as seen in Figure 2. Bolt 88 being carried by flanges 86K extending from the upper end of a presser plate 26K pivoted at its lower end at 17K will when moved to the right as aforesaid to draw the upper end of the presser plate 26K to the right 75

thus rocking the latter clockwise on its pivot mounting 17K. A set screw 27K is carried by the plate 26K adjacent the testing fingers 38 so that coins held on the legs 39K will, by reason of the rocking movement of the plate 26K, be pressed against the feelers 38 and by reason of a coin being located in the testing position, presser plate 26K will be limited in its movement. A pin 97 carried by flange 86K will urge a rod 98 pivoted at 99 counter-clockwise against the action of a spring 100, and by reason of the limited movement of the presser plate 26K the lower end of the rod 98 will be positioned directly above an opening 79K formed in the horizontal portion of a gate 40, pivoted at 17K thereby freeing gate 40 for pivotal movement by its spring 66K into a position to permit good coins to gravitate to the right of the gate 40. Facial readings of the coin by feelers 38 will cause the latter to pivot about annular ring 56K, the free ends of said feelers spreading or moving out from normal position, and upon proper facial reading one or more of the ends of said feelers 38 will abut rims 54B on collar 54K which under normal conditions would be urged to the left through its coupling with lever 58K, the latter of which is urged to the left by spring 66K when face 64K of plate 39 is depressed or dropped away from supporting engagement with detent 58A of the lever 58K. Such abutment of feelers 38 with the member 54b prevents the lower end of 58K from latching the horizontal arm of gate 40 against counter-clockwise movement thereby permitting the flag to assume a position where good coins will be dropped to the right of the vertical portion thereof. The downward movement of plate 39 through an extension 65E thereof engages a portion 130 of the lever 127K to pivot the latter clockwise and withdraw the legs 39K of the U-shaped member 38K, the bight portion of which is disposed in a yoke formed in the lever 127K. Downward movement of the plate 39 further releases a lever 85 pivoted at 86 for clockwise movement by spring 94 with nose 95A of said lever 85 pressing into the passage 36 to prevent additional coins from passing. Extreme downward movement of plate 39 causes finger 65b thereof to bear down on lever 89 to release the latter from latching engagement with bolt 88 thereby freeing pressure plate 26K and allowing the tested coin to gravitate to the right of the gate 40 out of the testing unit and into a passage 42, constituting a delivery chamber, the mouth 43 of which overlies the operating slide 25. If the testing apparatus is not properly actuated by the coin the gate 40 will not move from its position in Figure 2, with the result that the coin will gravitate down over the outer face 44 of a member defining the passage 42, thereafter being accessible to the patron through an opening 45 in the front of the housing.

In the event that the coin is accepted as aforesaid, its lower edge will rest on the operating slide 25 at the lower mouth 43 of the passage 42, and when the operating slide is fully retracted the coin will gravitate through the slot 29 between the fingers 28 and into the slot 20 in the slide 17 and rest on the floor 15 with the upper parts of the coin still projecting into the slot 20 and between the fingers 28, a pair of upstanding lugs 46 being provided at the rearward margins of the opening 20 as abutments against which the coin bears when the slides are moved together, so that the slides will be coupled for joint movement when the operating slide 25 is

subsequently pushed inwardly in the manner heretofore described, the coin ultimately finding its way through the openings 39 and 14 and into the coin box 13.

The coin depository 37 is automatically blocked when the supply of merchandise is exhausted, this being effected through the agency of a blocking rod 59 having an end portion slidable in a sleeve 51 extending transversely through the deposit opening, the opposite end of the rod being pivotally connected as at 52 with the upper end of a lever 53 which is pivoted as at 54 on the housing and which has a lower feeler end 55 disposed to engage an article of merchandise above the bottommost article in the stack. So long as there is an article to engage the feeler portion 55, the lever 53 will be pivoted in a clockwise direction to withdraw the end of the stopping rod 58 from blocking position across the coin depository, and when the next to last article is vended from the stack, the lever 53 is pivoted by a spring 56 (Fig. 1 also) to project the rod 59 in blocking position.

Means providing an operating connection between the slide 25 and the coin testing mechanism includes the provision of a dog leg lever 60 pivoted as at 61 on the testing unit and having a lower offset lug 62 on which is mounted a roller 63 disposed to be engaged by a cam member 64 which forms part of a cross strap 65 attached by means of screws 66 transversely on the slide 25. When the slide 25 is retracted (toward the left), the cam 64, bearing against the roller 63, pivots the lever 60 and the latter is provided with a horizontally projecting pin 67 engaged in the operating arm 39 of the testing unit, this operating arm being pulled downwardly each time the manual operating slide is retracted to effect operation of the various testing mechanisms employed in the device 35.

A lever 70 pivoted as at 71 on a post 72 mounted on the housing wall, has a free end portion 73 projected in a slot 74 disposed in a horizontally offset flange 75 on the transverse strap 65, and the lever 70 is urged in an anti-clockwise direction by a coil spring 76 disposed on a post 77 having a slot 78 in which the lever 70 works against the spring, the result being that the manual operating slide 25 is urged into its normal position, as seen in Figs. 1 and 2, by the lever 70 and the spring 76.

Means for preventing the release of a coin from the testing device, or, in other terms, the delivery of a coin by the testing device, for movement into coupling relation with the slides, includes an offset pawl or feeler 80 (Fig. 2 particularly) pivotally mounted as at 81 beneath the testing device and having a nose portion normally projecting into a slot 82 at one side of the lower coin delivery passage 42. The dog leg lever 60 is provided with an offset lug 83 extended to bear against the feeler 80 to project the latter in a direction to dispose its nose in the slot 82. If there is a coin in the lower portion of the chamber 42 as a result of the control slide being in a position where the coin slot thereof is out of register with the mouth 43, the feeler 80 cannot move, and as a result, the offset 83 on the dog leg cannot move upwardly and therefore the operating arm 39 of the coin testing device cannot be raised to normal position. As a result of the foregoing inability of the arm 39 to return to normally raised position, and due to the fact that the coin testing device is pro-

vided with a blocking finger 85 which is pivoted as at 86 and arranged to be projected into blocking position across the coin chamber 36 when the main operating arm 39 of the testing device is lowered as aforesaid, no coins can pass from the depository 37 in the housing through the testing chamber 36 toward the operating slides so long as a coin is retained in front of the nose of the feeler lever 80.

10

Operation

Assuming articles of merchandise M to be disposed in the magazine of the vending machine, the patron deposits a proper coin element in the opening 37, and this coin element descends into a position substantially opposite the testing feelers 38 where the coin is held by horizontally slidable pins. Thereafter, the operator will grasp the handle on slide 25 and retract the latter toward the left, which action will cause the cam 64 to bear against the roller 63 and pivot the dog leg 60 so as to pull the tester operating plate 39 downwardly, this latter operation causing the coin to be pressed against the feelers 38 and the withdrawal of the sustaining pins substantially at the same time, so that the coin is tested and released for descending movement toward the gate 40. If the coin is of acceptable nature, the testing apparatus will have conditioned the mechanism so that the gate 40 will be pivoted out of the path of the coin when the latter is freed so that the coin will descend into the passage 42 past the nose of the feeler 80 into the slot 29 and down into the slot 20 on the ejecting or actuating slide, and upon inward movement of the operating slide 25, the coin is urged by the pins 28 against the margins of the slot 20 and the lugs 46 so that the ejecting slide is carried with the control slide for the purpose heretofore set forth, the formations 31-32 preventing return movement of the coin once it has been moved a certain distance toward its ultimate goal.

When a coin is deposited through the opening 37 it descends into the chamber 36 to rest on the horizontal pins (not shown) so that the coin will be held opposite the fingers 38. Should a second coin be deposited before the first coin has left the testing chamber, the second coin will rest on the upper edge of the first coin. When the operating slide 25 is retracted (toward the left), the first coin will be pushed against the testing fingers 38 and substantially at the same time the horizontal pins will be withdrawn from supporting position beneath the coin, and the gate 40 will open (provided the coin is acceptable) to permit passage of the coin into the chamber 42; also, at this time, the blocking lever 85 will move its nose portion across the upper part of the chamber 36 against the second coin so that the latter will be prevented from descending until the horizontal pins are restored to normal position. Likewise, any coins resting above the second coin will be prevented from moving downwardly by the blocking lever 85, it being pointed out that the leverages for operating the lever 85 are such that the slightest retractive movement of the slide 25 will cause the blocking lever 85 to move into blocking position.

So long as the operator moves the slide 25 back and forth in complete strokes, the coins will be fed in an orderly fashion one at a time into and past the testing chamber. However, should the operator manipulate the slide so as to cause the

coin to be tested and released for movement down into the chamber 42 where it will rest on the slide 25, and then, instead of completing the retractive movement of the slide 25, start to return the slide (toward the right), any subsequently deposited coins in the chamber 36 might be tested and released so as to stack up above the chamber 42 and become jammed in the latter, thereby creating a danger of putting the machine out of commission or the failure of the machine to deliver an article for each coin deposited. The mechanism 80-83 prevents operation of the coin testing device so long as a coin rests in the region of the mouth 43 of the chamber 42, the nose of the feeler or dangler 80 being prevented from moving into the slot 82, with the result that the dog leg lever 60 is prevented by abutment of its offset 83 against the feeler 80 from being raised, and as a consequence the operating plate 39 of the testing device cannot be raised. Thus, so long as a coin remains in blocking position in front of the nose of the feeler 80, the blocking lever 85 will remain in blocking position, and a complete operating stroke of the manual slide 25 must be made in order to free subsequent coins for movement into coupling position relative to the slides.

This application claims as novel the combination of coin-operated locking means, such as the structure 80-83, with coin-coupled operating members and a coin testing device arranged to deliver coins into coupling relation with said members.

The objects and advantages of the invention may be accomplished by variations in the form, location, and operation of the specifically described embodiment set forth herein, and it is a condition of this disclosure that all equivalent means and arrangements are to be included within the call of the appended claims.

Having thus described my invention, what I claim as new and desire to protect by Letters Patent is:

1. In a device of the class described including a coin testing means having an operating control and mechanism operable thereby for testing and delivering coins one at a time to a predetermined position, and cooperating slide members arranged to be coupled for joint movement by a coin received from said predetermined position, together with lever means operatively connected to said operating control, said lever means being disposed for operative engagement with one of said cooperating slides to operate the operating control when said slides are moved toward said coin receiving position, the combination of means for preventing a second operation of said operating control before a coin is received from said predetermined position by said cooperating slides, said last named means comprising a feeler pawl pivotally arranged adjacent said predetermined position and having one end portion engageable with said lever means and adapted to block return movement of the latter and an opposite end portion disposed in said predetermined position and adapted to abut a coin to dispose said feeler pawl in blocking relation with respect to said lever means for the purpose aforesaid.

2. In a coin control device including mechanism for testing coins including an operating member for effecting delivery of acceptable coins to a certain position, and coacting control slides arranged to be coupled by a coin received in operative engagement therewith from said certain

position, one of said coacting slides having a coin receiving pocket formed therein and normally disposed with said pocket out of alignment with said certain position, said coin gravitating from said position by movement of the said one of the coacting slides to couple the slides, the combination of means operatively connected to the operating member and having a portion thereof engageable by said one of said slides for movement by the latter to operate the operating member for the purpose aforesaid, and a feeler pivotally arranged adjacent said certain position and having a portion thereof normally disposed in said certain position to engage a coin and engageable with said last named means to obstruct movement of the latter so long as a previously delivered coin remains in said certain position.

3. In combination, coin testing means of a type including operating means and mechanism actuated thereby to test and release a coin for gravitating movement into a predetermined position, mechanism operatively connected to said operating means and arranged to engage a coin at said position and prevent effective actuation of said operating means whereby to prevent release of additional coins for movement toward said predetermined position until the first-mentioned coin is removed from said position, and coacting movable actuating members arranged to be coupled for joint movement by a coin element received into operative coupling engagement therewith from said particular position, said coacting members being arranged to receive a coupling coin from said position, and one of said coacting members being operatively associated with said mechanism to effect actuation of the said operating means.

4. In a coin-controlled device, the combination of a coin testing mechanism including a testing means and having an operating member movable from a normal position to actuate said testing means and effect testing and delivery of a coin therefrom, a delivery chamber adapted to receive coins from said testing mechanism, and a pair of control slides positioned relative to said delivery chamber to receive a coin gravitating from the latter, said slides being coupled for joint control actuation by a coin received from the delivery chamber as aforesaid, link means operatively connecting said operating member with one of said slides, means in said testing mechanism actuated cooperably with said operating member when the said pair of slides are moved toward coin receiving position to prevent passage of a second coin following a tested coin to said delivery chamber so long as said operating member is disposed out of normal position to actuate said testing mechanism, and means in the nature of a feeler operatively associated with said link means arranged to engage a coin in said delivery chamber and prevent restoration of said operating member to normal position so long as a coin remains in the delivery chamber.

5. Coin-controlled mechanism comprising, in combination, a pair of reciprocal members arranged to be coupled for joint movement by a coin and movable into a normal relative position to receive a coin, and testing apparatus including testing means and an operating member therefor, and linking means connected to said operating member and operably associated with one of said reciprocal members for actuation by the latter from a normal position when the same is moved toward normal coin receiv-

ing position, said testing apparatus being arranged to test a coin and effect movement of an acceptable tested coin into a certain position for movement into coupling engagement with the reciprocable members as aforesaid, means in said testing apparatus engageable by said operating member and releasable for preventing passage of additional coins therethrough while said operating member is in operated condition, means including a feeler lever adapted to abut said linking means and situated to engage a coin disposed in said certain position, said feeler lever coacting with said linking means to prevent movement of the operating member from operated condition back to said normal position so long as there is a coin engaging said feeler lever at said certain position.

6. In a coin-controlled device, in combination, coin testing means including a testing chamber, means for testing a coin in said chamber, releasable means coacting with said testing means for holding a coin in said chamber prior to operation of the testing means, an operating member arranged to actuate said testing means and subsequently release said releasable means, a delivery chamber below said testing chamber, ac-

ceptable coins tested and released as aforesaid gravitating into said delivery chamber below said testing chamber, means for holding a second coin in said testing chamber while said operating member is in operated condition to effect release of a tested coin whereby said second coin will be prevented from passing into said delivery chamber while said operating member remains in operated condition, coin coupled control means 5 slidably arranged below said delivery chamber and of a type having a coin receiving aperture formed therein and utilizing a coin for effective control operation and adapted to receive a tested coin from said delivery chamber, a feeler positioned to engage a coin in said delivery chamber, and means operably engageable by said control means and connected to said operating member for actuation of the latter by the former, said last named means being adapted to be affected by 10 said feeler means to cooperate with said operating member and coin testing means to prevent release of said second-mentioned holding means so long as a coin remains in the delivery chamber.
